DIFFERENTIAL DRUM FOR MINE ANCHORS

James B. Glennon, United States Navy

Application September 27, 1932, Serial No. 635,117

9 Claims. (Cl. 102—13)

(Granted under the act of March 3, 1883, as
amended April 30, 1928; 370 O. G. 757)

1

This invention relates to a drum for mine anchors so constructed that the mine anchor cable is paid out at different rates and has for its object to provide a means that will cause the mine case to separate from its anchor at different speeds during various stages of the unwinding of the anchor cable.

With the above and other objects in view, the invention consists in the construction, combination and arrangement of parts as will be described more fully hereinafter.

The drawing shows one embodiment of my invention.

In mine assemblies designed to go to the bottom before the mooring cable drum is locked, it is necessary to have several major changes in the rate at which the mine case separates from the mine anchor. At first the mine case and the anchor must separate rapidly until a few feet apart, thus avoiding damage to the mine case when the anchor strikes a hard bottom, as well as avoiding immersion of the mine case in a soft muddy bottom. Next the mine and anchor must separate slowly so that there is no possibility that the mine will return and damage the mine layer (especially a submarine mine layer) during a shallow water plant. Then the mine must finally ascend to its proper level in a brief period even where depths are great, for during this interval the mine is exposed to sweeping operations but is too deep to be effective against an enemy vessel.

The force acting on the mooring cable drum consists of the pull of the anchor cable, due in general to the buoyancy of the mine case, and the retarding force caused by the action of the brake provided to control the rate of unwinding of the cable. Assuming that both these forces remain constant, the rate of turning of the drum will be proportional to the lever arm of the pull of the mooring cable, i. e., to the radius of the cylinder upon which the cable is wound, which may be either the drum itself or a cylinder built up by layers of the mooring cable itself on the drum. Further, the rate of separation of the case from the anchor per turn of the drum will also be proportional to the same radius since this fixes the length of cable unwound by each turn of the drum. Therefore, the rate of separation of the case from the anchor will vary directly as the square of the radius of the cylinder on which the cable is wound. This is the principle upon which the functioning of my invention depends.

The drum, which is suitably mounted in frame members 1, comprises three sections; a section 2 of relatively large diameter, a section 3 of small

2

diameter and a section 4 of diameter intermediate those of the other two sections. In winding the cable 8 on the drum the major part thereof is placed on section 4, then the cable is engaged in a slot in disk 5 to prevent its slipping and the desired length wound on section 3, the cable is engaged in a slot in flange 6 on section 2 and two or three turns placed on section 2. The end of the cable is then passed under guide 7 and up through the fairlead to the eye 7' on the lower portion of the mine M to which the end is attached.

As the case begins to separate from the anchor, the cable will first unwind from section 2 which, being of large diameter, will pay out the cable rapidly and will permit the case to separate from the anchor before the anchor strikes bottom.

While the cable is unwinding from section 3 the case and anchor will separate slowly, due to the small radius of that part of the drum. The time consumed in unwinding this portion may easily be made five to ten minutes, thus there will be no likelihood of the mine rising rapidly enough to contact the mine layer.

Thereafter, the mine laying vessel having had sufficient time to move out of danger from the mine, the remainder of the cable will be released from the part 4 of the drum with relative rapidity and the mine will quickly reach its final position.

The rate at which the cable runs out is controlled by the brake mechanism comprising a rotatable paddle wheel 9 connected through the power reducing gearing train 10 to gear wheel 11 on the drum. A protective housing 12 is disposed around wheel 9 to prevent fouling of the wheel, it being understood that water has ready ingress to and egress from the housing. A fixed paddle wheel 13 is mounted in housing 12 to prevent free circulation of the water therein and to set up turbulences in the water to increase the braking effect of the paddle wheel 9.

It is apparent that when a mine connected to its anchor by a cable wound on a drum as herein shown is launched, the large radius of the part 2 of the drum will afford a long lever arm and so the pull of the mine on the cable will rotate paddle wheel 9 at a relatively high rate and due to the length of cable unwound from part 2 at each revolution, the mine and anchor will rapidly separate. The power afforded by the small radius of part 3 of the drum, together with the short section of cable unwound by each revolution, will greatly retard the rate of paying out of the cable from that part. The major portion of the cable is then unwound at a rate intermediate the two

previously mentioned until the mine reaches the depth for which the mechanism is set, when the cable is locked.

It will be understood that the above description and accompanying drawing comprehend only the general and preferred embodiment of my invention, and that various changes in construction, proportion and arrangement of parts may be made within the scope of the appended claims without sacrificing any of the advantages of this invention.

The invention described herein may be manufactured and used by or for the Government of the United States of America for governmental purposes without the payment of any royalties thereon or therefor.

I claim:

1. A differential drum for mine anchors, comprising a rotatably mounted member having a portion of relatively large radius to carry a small number of turns of cable, a portion of small radius adjacent thereto to carry a moderate number of turns of cable, a portion of radius intermediate the radii of the two above mentioned portions to carry the major portion of the cable, a guide around which the cable may run, a housing, a fixed paddle wheel in said housing, a rotatable paddle wheel in said housing, and a gear train connecting said rotatable wheel with said rotatably mounted member.

2. A differential drum for mine anchors, comprising a rotatably mounted member having a portion of relatively large radius to carry a small number of turns of cable, a portion of small radius adjacent thereto to carry a moderate number of turns of cable, a portion of radius intermediate the radii of the two above mentioned portions to carry the major portion of the cable, a guide around which the cable may run, and means connected to said rotatably mounted member adapted to act upon water in which said drum is immersed to exert a braking effect upon said rotatably mounted member.

3. A differential drum for mine anchors, comprising a rotatably mounted member having a portion of relatively large radius to carry a small number of turns of cable, a portion of small radius adjacent thereto to carry a moderate number of turns of cable, a portion of radius intermediate the radii of the two above mentioned portions to carry the major portion of the cable, a guide around which the cable may run, and means to retard the rotation of said rotatably mounted member.

4. A differential drum for mine anchors, comprising a rotatably mounted member having a portion of relatively large radius, a portion of intermediate radius, and a portion of relatively small radius disposed between the aforesaid two portions, and means adapted to act upon water in which said drum is immersed to effect a braking action on the said rotatably mounted member.

5. A differential drum for mine anchors, comprising a rotatably mounted member having a portion of relatively large radius, a portion of intermediate radius, and a portion of relatively small radius disposed between the aforesaid two portions, and means to retard the rotation of said rotatably mounted member.

6. A differential drum for mine anchors, comprising a rotatably mounted member adapted to have wound on it the anchor cable, the said mem-

ber having portions of different radii whereby the said cable will be unwound therefrom at different rates from the portions of different radii and means comprising a rotatable paddle wheel driven by said member and a fixed paddle wheel adjacent thereto, all said portions being rigidly connected together.

7. In a device for paying out a mine anchor cable, means to pay out a portion of said cable at a relatively rapid rate, then a second portion slowly, and then the major portion at a rate intermediate the two previously mentioned rates, and means including a rotatable paddle wheel driven by said first mentioned means and a fixed paddle wheel adjacent thereto acting upon the water in which the mine is being planted to retard the paying out of the cable.

8. A device of the character disclosed for mooring a buoyant mine within a body of water comprising a mine anchor, a rotatable drum arranged within said mine anchor adapted to unwind a length of cable therefrom, a buoyant mine secured to said cable, a device operatively connected to said drum adapted to act upon the water for retarding the rotation of the drum variably in response to changes in the turning moment applied thereto by said buoyant mine when the device has been launched within the body of water, means for causing a first length of cable to be paid out from the mine anchor at a relatively fast rate, means for causing a succeeding length of the cable to be paid out from the mine anchor at a relatively slow rate, and means for causing the remainder of the cable to be paid out from the mine anchor at an intermediate rate, all of said means being arranged on said rotatable drum.

9. In a mine assembly comprising a mine anchor having a buoyant mine normally resting thereon, a mooring cable having one end thereof secured to the mine and the major portion of the cable arranged within said mine anchor, means for paying out said cable from the mine anchor as the mine and anchor are launched within a body of water, means arranged within the mine anchor for causing the mine to be separated from the anchor at a relatively high rate until a predetermined length of cable has been paid out from the mine anchor, means controlled by the cable for causing the mine to separate from the anchor at a considerably slower rate until a predetermined additional length of cable has been paid out from the mine anchor, and means controlled by the cable for causing the mine to be separated from the mine anchor at an intermediate rate while the remaining cable is being paid out from the mine anchor.
